UNITED STATES PATENT OFFICE.

WILLIAM B. STEPHENSON, OF CHICAGO, ILLINOIS.

ROOF FLASHING.

Application filed March 19, 1928. Serial No. 262,742.

This invention relates to roof flashings, one of which is adapted to maintain a watertight joint between a roof and a pipe, such as a ventilating pipe, projecting substantially vertically therethrough.

These flashings commonly comprise a flat base plate which is anchored in or upon the roof materials, and a sleeve portion which may consist of a plurality of inter-engaged members, the sleeve portion projecting upwardly from the base and usually having a generally conical form, the smaller upper end of the sleeve being tightly secured about the pipe, usually by means of a soft metal collar which is calked to the pipe. The pipe, which extends downwardly through the flashing and an opening in the roof, is usually supported from below independently of the roof, and if the roof should settle an appreciable amount, or change its angular relation to the pipe, the joint between the collar and the pipe will be broken away unless the sleeve is provided with some form of telescopic or sliding connection to allow for these relative movements between the roof and pipe. A flashing provided with such a telescopic connection is disclosed in the patent to Robert J. Stephenson, 1,587,250, granted June 1, 1926, the present invention relating to certain improvements in the type of roof flashing covered by that patent.

The principal object of the present invention is to provide a roof flashing of this general type adapted for use with roofs of various inclinations. In general terms, the sleeve member consists of a plurality of annular sections, the upper end of the uppermost section being anchored in the soft metal collar which engages the pipe, and the lower end of the lowermost section being secured about the periphery of the opening of the base plate. A telescopic connection is provided between two of the sleeve sections to accommodate the relative vertical movements between the roof and pipe. A rotary connection between another pair of the sections is positioned in a plane at an angle to the central axis of the sleeve members, so that the inclination of the axis of the clamping collar and telescopic connections with relation to the roof or base plate can be varied. A third connection between a pair of the sleeve sections permits a limited tilting

movement between these sections to accommodate a small change in the angular relation between the roof and pipe, or to originally adapt the flashing for use with roofs of varying inclinations. The general object is to provide separate connections for accommodating the flashing to use with different roof angles, without necessitating any tilting movement between the members of the telescopic joint, the axis of this joint being maintained substantially coincident with the central axis of the pipe so that there will be no binding between the members of the telescopic connection.

Other objects and advantages of this invention will be apparent from the following detailed description of one approved form of the device.

In the accompanying drawings:

Fig. 1 is a plan view of the flashing as applied to a horizontal roof and a vertical pipe.

Fig. 2 is a central vertical section taken substantially on the line 2—2 of Fig. 1.

Fig. 3 is a side elevation of the flashing as applied to a vertical pipe and a roof extending at substantially 45° to the vertical or horizontal.

Fig. 4 is a partial central vertical section, corresponding to the upper portion of Fig. 2, but showing the use of the upper tilting connection.

The base 1 of the flashing is in the form of a rectangular sheet metal plate, which is anchored to the roof in any suitable manner usually being secured between the roof and the shingles or other roof covering. The plate 1 is formed with an elliptical opening 2, large enough to permit the pipe 3 to pass through at various angles. A soft metal collar 4 is adapted to be clamped securely about the pipe 3. This collar will initially have an inner diameter (particularly at its lower end) somewhat larger than the diameter of the pipe 3, but the collar is formed of lead or other suitable soft metal, and a clamping means is provided for contracting the upper portion of the collar and forcing same into snug engagement with the pipe. In the form here shown, a split wire ring 5 surrounds the upper portion of the collar 4, the eyes 6 at the ends of the split ring 5 being adjustably connected by a screw bolt

7. By tightening this bolt the ring 5 may be contracted about the soft metal collar 4, thus forcing the collar into engagement with the pipe, after which the upper end of the 5 collar may be calked tightly to the pipe.

A sleeve member of generally conical form connects the collar 4 with the base plate 1 so as to prevent water from passing downwardly about the pipe 3 through the roof 10 opening 2. This sleeve consists of a plurality of annular sections, formed and connected as hereinafter specified in detail.

The lower sleeve member 8 is in the form of the frustum of a cone, the lower larger 15 end of the sleeve being secured about the edges of the opening 2 in base plate 1 in any suitable manner, usually by crimping the edges of the sleeve and plate together as indicated at 9. The sleeve 8 might be stamped 20 integrally from the base plate 1, thus entirely eliminating the joint mentioned. The upper open end of sleeve 8 terminates in an outwardly extending annular flange 10, which lies in a plane having an angle of sub- 25 stantially $22\frac{1}{2}^\circ$ with the plane of the base plate 1. A second, substantially cylindrical, sleeve member 11 has its upper open end provided with an outwardly extending annular flange 12 lying in a plane perpendicular to the axis of the cylinder. The lower end of the sleeve member 11 terminates in a plane extending at an angle of $22\frac{1}{2}^\circ$ to the axis of the cylinder, this end of sleeve 11 being flared or crimped so as to extend out- 30 wardly and then inwardly around the flange 10 on the lower sleeve member 8. The lower end 13 of cylindrical sleeve 11 is not crimped tightly to the flange 10, but the flange 10 is capable of sliding in the recess formed at 35 the lower end of member 11 so that the lower end of member 11 may be rotated about the upper end of member 8. With the parts in the position shown in Fig. 2, the angle at the lower end of sleeve member 11 counter- 40 acts the angle at the upper end of sleeve member 8 so that the vertical axis of cylinder 11 is substantially perpendicular to the plane of base plate 1. If the sleeve member 11 is rotated through 180° with relation to the sleeve member 8, the two angles will 45 be added together so that the axis of the cylinder 11 will be at an angle of substantially 45° to the base plate 1, as shown in Fig. 3.

55 A third sleeve member 14, of hollow cylindrical form, is formed with an inwardly extending annular flange 15 at its lower end and an outwardly extending annular flange 16 at its upper end. The sleeve member 14 60 is of sufficient inner diameter to fit loosely about the outer periphery of flange 12 at the upper end of sleeve 11, and the inwardly extending flange 15 on sleeve member 14 has an inner diameter slightly larger than the 65 outer diameter of sleeve 11, whereby the an-

nular flanges 12 and 15 will overlap to prevent complete separation of the two sleeve members 11 and 14, but these members are free to telescope one within the other in a direction parallel to the longitudinal axis of 70 the cylindrical members.

Sleeve member 17 is secured at its upper end to the soft metal collar 4, preferably by having this end of the sleeve member imbedded within the soft metal of the collar. 75 The lower end of sleeve member 17 extends outwardly at 18, downwardly at 19, and inwardly at 20, to form an inner annular recess 21 for receiving the outwardly projecting flange 16 at the upper end of sleeve member 14. This lower portion of sleeve 17 fits rather snugly about the outer periphery of flange 16, but the recess 21 is of considerably greater height than the thickness of the flange 16 so that the flange may be tilted 80 therein, for example as indicated in Fig. 4, so as to displace the central axis of sleeve member 17 and clamping collar 4 angularly with relation to the axis of cylindrical sleeve 14. 85

It is desirable that when this assembled flashing is installed between the pipe and roof, the longitudinal axis of the cylindrical sleeve members 11 and 14 shall be substantially coincident with or parallel to the axis of pipe 3, so that as the roof settles with relation to the pipe, the telescoped sleeve members may freely slide over one another without danger of binding. It will be seen that with the parts positioned as shown in 90 Figs. 1 and 2 this desired relation of the telescoping members with respect to the axis of the pipe is obtained for substantially flat roofs, that is when the roof is horizontal and the pipe vertical. With the members adjust- 95 ed as shown in Fig. 3, that is when sleeve member 11 has been rotated 180° from the position shown in Fig. 2, the same relation between the upper sleeve members and the pipe obtain as in the Fig. 2 position but the 100 base plate 1 is adapted for a 45° roof angle. By tilting the upper sleeve member 17 and clamping collar 4 with relation to the upper cylindrical sleeve 14, as shown in Fig. 4, the 105 flashing may be used on roofs having angles 110 intermediate or varying from the horizontal and 45° angles shown in Figs. 2 and 3. This 115 tilting connection between the two upper sleeve members will also accommodate tilting movements of the pipe with relation to the roof, or vice versa, after the device has 120 been installed. In other words, if the roof settles at an angle, as is often the case, this relative tilting movement can be accommodated by the connection between sleeves 14 and 17 without causing binding between the 125 telescoped sleeve members 11 and 14. A certain amount of angular adjustment is also possible between these telescoped members, but it is desirable to take up this angular ad- 130

justment between the sleeves 14 and 17 rather than between the telescoped sleeve members, for reasons already specified.

It should also be noted that the sleeve sections are all of materially greater inner diameter than the outer diameter of pipe 3, so that an appreciable angular tilting of the pipe 3 in the soft metal collar 4 may be utilized when the flashing is installed to help adjust the device to the angle of any particular roof. All of these features provide a considerable range of adjustability to this flashing so that the flashing may be used on a roof of any angle normally encountered without relatively tilting the two telescoping sleeve members 11 and 14 or varying their angle with relation to the axis of the parts to an extent sufficient to cause binding in the telescopic connection.

20 I claim:

1. A roof flashing comprising a flat metal base plate adapted to be mounted on the roof, a soft metal collar adapted to be clamped about a pipe, and a sleeve connecting the plate and collar, the sleeve consisting of a plurality of annular sections, two of the sections overlapping so that they are capable of free telescopic movement one into the other, and a second connection between two of the sections permitting relative tilting movement between these members to accommodate different inclinations of the pipe with relation to the base plate.

2. A roof flashing comprising a flat metal base plate adapted to be mounted on the roof, a soft metal collar adapted to be clamped about a pipe, and a sleeve comprising a plurality of annular sections, the upper end of the upper section being secured to the collar, and the lower end of the lower section being secured about an opening in the base plate, each adjacent pair of sections being connected by having the lower end of the uppermost section overlap the upper end of the next lower section, one of these overlapping connections being formed to permit telescopic movement of the sleeve members so that the collar may move toward or from the plate, and another connection permitting relative tilting movement between the connected sleeve members.

3. A roof flashing comprising a flat metal base plate adapted to be mounted on the roof, a soft metal collar adapted to be clamped about a pipe, and a sleeve comprising a plurality of annular sections, the upper end of the upper section being secured to the collar, and the lower end of the lower section being secured about an opening in the base plate, each adjacent pair of sections being connected by having the lower end of the uppermost section overlap the upper end of the next lower section, one of these overlapping connections being formed to permit telescopic movement of the sleeve

members so that the collar may move toward or from the plate, another connection permitting relative tilting movement between the connected sections, and a third connection permitting relative rotary movement at an angle to the central axis of the sleeve members.

4. A roof flashing comprising a base in the form of a flat metal plate, a sleeve member in the form of a truncated cone, the larger lower end extending from the edges of an opening in the base-plate, the smaller upper end lying in a plane at substantially $22\frac{1}{2}^{\circ}$ to the plane of the base-plate, a second substantially cylindrical sleeve member having its free upper end in a plane substantially perpendicular to the axis of the cylinder, and its lower end lying in a plane at substantially $22\frac{1}{2}^{\circ}$ to this axis and rotatably joined to the upper end of the first sleeve member, whereby in one position the upper end of the second sleeve member will be substantially parallel to the base plate and when the second member is rotated through 180° from this position its upper end will lie in a plane at substantially 45° to the base plate, the second sleeve member having an outwardly projecting annular flange at its free upper end, a third substantially cylindrical sleeve member of greater internal diameter than the outer diameter of the flange on the second member, said third sleeve member having an inwardly projecting flange at its lower end freely engaging about the second sleeve member beneath the flange thereon, whereby the second and third members may freely telescope within one another in the direction of their cylindrical axes but are prevented from complete separation by the overlapping flanges, a soft metal collar adapted to be clamped about a pipe, and means connecting said collar with the upper end of the third sleeve member.

5. A roof flashing comprising a base in the form of a flat metal plate, a sleeve member in the form of a truncated cone, the larger lower end extending from the edges of an opening in the base-plate, the smaller upper end lying in a plane at substantially $22\frac{1}{2}^{\circ}$ to the plane of the base-plate, a second substantially cylindrical sleeve member having its free upper end in a plane substantially perpendicular to the axis of the cylinder, and its lower end lying in a plane at substantially $22\frac{1}{2}^{\circ}$ to this axis and rotatably joined to the upper end of the first sleeve member, whereby in one position the upper end of the second sleeve member will be substantially parallel to the base plate and when the second member is rotated through 180° from this position its upper end will lie in a plane at substantially 45° to the base plate, the second sleeve member having an outwardly projecting annular flange at its free upper end, a third substantially cylindrical

sleeve member of greater internal diameter than the outer diameter of the flange on the second member, said third sleeve member having an inwardly projecting flange at its lower end freely engaging about the second sleeve member beneath the flange thereon, whereby the second and third members may freely telescope within one another in the direction of their cylindrical axes but are prevented from complete separation by the overlapping flanges, there being an outturned annular flange at the upper end of the third

sleeve member, a fourth sleeve member having an internal annular recess in its lower portion of greater height than the thickness of the last mentioned flange, in which recess the flange is engaged whereby the third and fourth sleeve members may be tilted out of axial alignment with one another without becoming disengaged, a soft metal collar secured at the upper end of the fourth sleeve member, and means for clamping this soft metal collar about a pipe.

WILLIAM B. STEPHENSON.
